PLATING DEVICE FOR KNITTING MACHINES

Michael Zimic, Forest Hills West, and Anton Miskovsky, Astoria, N. Y.; said Miskovsky assignor to said Zimic

Application July 16, 1937, Serial No. 153,914

5 Claims. (Cl. 66—126)

This invention relates to improvements in the art of knitting and has particular reference to a plating device for knitting machines.

In plating operations as heretofore conducted, it has been the practice to feed two yarns, usually of different colors, to a single guide mounted upon a carrier which reciprocates over the needles of the machine to draw the yarns thereafter as they are fed to the needles. The two 5 yarns are led through openings in the guide with one yarn longitudinally spaced from the other at the point of exit from the guide and disposed slightly above the other as the yarns extend from the guide toward the needles in converging relation and in a direction opposite to that of the travel of the guide, so that said yarns will be laid upon the needles in such manner as to obtain the usual plating effect when the needles are operated to form the loops in the knitted fabric. 10 When the movement of the guide is reversed at either end of its reciprocating stroke to initiate the knitting of a succeeding course in the fabric, there occurs an initial slackening in the tension on the yarns while the carrier starts its movement in the opposite direction and until the 15 yarns are again tautened by said movement, following which the yarns are again fed to the needles until the carrier reaches the other extreme of its travel. In the usual yarn guide employed for this operation, the two yarns pass therethrough and extend toward the needles in close proximity to each other and at the beginning of the reversal of the carrier and while the 20 yarns are slackened, one of them crosses or passes the other in the guide so as to assume the same relative position to the latter yarn as during the previous movement of the carrier guide in the opposite direction.

One of the major difficulties in plating which 25 has not been completely solved is the improper feed of the yarns to the needles which results in the formation of loops in a course being knitted wherein the positions of the yarns become reversed on the needles so that the wrong color of 30 the yarn appears on each surface of the fabric, thus destroying the continuity of color effect. When this occurs, the imperfectly knitted section of the fabric must be removed from the piece when used and this results in considerable loss of 35 material. It has been found in actual practice that this imperfect knitting usually occurs at the beginning of the knitting of a course and will often run through the entire length thereof and sometimes into the following course; and again, 40 the imperfection may start in the middle of a

course. It is quite difficult to determine the causes of this improper knitting, particularly when it starts at an intermediate point, but it appears that when the yarns are incorrectly fed to the needles at the beginning of a course, this 5 is due to the same becoming twisted one with the other during the time when they are slackened and are altering their relative positions in the guide, so that they are fed to the needles in reversed position. When an imperfection starts at 10 an intermediate point in a course, it is believed to be due to the fact that the portions of the yarns extending from the guide to the needles and which are tautened at this time, are in such close 15 proximity that the vibrations of the machine imparted to the yarns cause the same to come into contact with each other in advance of the point where they engage the needles, and thereby become twisted so that the correct positions at the 20 needles are reversed.

Whatever may be the underlying reasons for the formation of these imperfections, it has been discovered, in actual practice, that the same may be avoided by employing two separate guides for the yarns and mounting the same so that prior 25 to the commencement of the knitting of each course in a fabric, which occurs when the direction of movement of said guides is altered, the positions of said guides relative to each other are reversed in order that the yarns will, at all times, 30 be fed to and engaged with the needles of the machine in a definite order and be prevented from becoming twisted one with the other.

The inventive idea herein involved is capable of receiving a variety of expressions some of 35 which, for purposes of illustration, are shown in the accompanying drawings wherein—

Figure 1 is a side elevation of one form of the invention in which a single yarn carrier is provided with two guides shown in the positions 40 which they assume when the carrier is being moved to the right, as indicated by the arrow, by a well known type of propelling mechanism illustrated in fragmentary elevation in said figure.

Figure 2 is a view of the yarn carrier similar to 45 that shown in Figure 1 with the relative positions of the guides reversed, as when the carrier is being moved to the left as indicated by the arrow.

Figure 3 is an elevational view, partly broken away and shown in section, of the opposite side 50 of the yarn carrier from that viewed in Figure 1.

Figure 4 is a transverse section on the line 4—4 of Figure 3.

Figure 5 is a horizontal section on the line 5—5 of Figure 1.

Figure 6 is a vertical transverse section through the yarn carrier and a portion of its propelling means.

Figure 7 is a view similar to Figure 6 showing a different form of plating device in which a separate yarn carrier is provided for each of the guides, and

Figure 8 is a side elevation of the carriers as shown in Figure 7, the view indicating the positions of the guides when the carriers are being moved in unison in a right hand direction, as in Figure 1.

In carrying out the invention one method of procedure, as illustrated in Figures 1 to 6, may be to mount two yarn guides 10 and 11 on a single carrier, generally indicated by the numeral 12, in such manner that when the direction of movement of the carrier is altered at the end of a stroke of its reciprocation, the relative positions

of the guides are reversed, as will be noted from an inspection of Figures 1 and 2, so that one of the guides will always follow the other with respect to their longitudinal disposition, regardless of the direction of movement of the carrier. Thus, as in Figure 1, in which the carrier is indicated as traveling to the right, the guide 10 precedes the guide 11 so that the yarns 13 and 14 extending from their respective guides will be longitudinally spaced at their point of exit from said guides and will then extend toward the needles of the machine, conventionally indicated at 15, in a direction opposite to that of the travel of the guides, said yarns gradually converging toward said needles in the customary manner

so as to be properly engaged therewith preparatory to the formation of loops. When the carrier 12 has reached the right hand end of its stroke or travel and is ready to make its return movement to the left, as indicated in Figure 2,

the propelling means for the carrier also reverses

its movement and in so doing initially adjusts

one member or portion of the carrier 12 which

carries the guide 10 longitudinally of another

member of said carrier which supports the guide

11. During this relative movement of the two

members of the carrier the guide 10 is shifted

from the position of Figure 1 to that of Figure

2. At the conclusion of this reversal of the

relative positions of the guides the propelling means

then moves the members of the carrier in unison

and the guide 11 consequently follows the guide

10 across the machine to the left in the same

manner as when the previous course in the fab-

ric was being knitted. During the reciprocation

55 of the carrier, the two guides 10 and 11 are in

substantially longitudinal alinement with each

other, as best shown in Figure 5, and in order

that the change-over or reversal of the positions

may be effected, as progressively indicated in

60 dotted lines in the latter figure, the two guides

are carried by arms 16 and 17, respectively, of

spring metal which allow said guides to be flexed

transversely or laterally with respect to their

longitudinal line of travel; and to further facil-

itate the passage of the guides, the vertical edges

18 thereof are beveled, as also best shown in

Figure 5, so that when these edges contact each

other during the relative movement of the guide

10 the latter will freely pass the guide 11 without

70 being obstructed thereby and the two yarns 13

and 14 will be maintained out of contact with

each other.

The yarn carrier 12 is slideably mounted upon one of the customary trackways 19 which extend longitudinally of the machine and comprises,

generally, two members 20 and 21, the latter of which is mounted for limited longitudinal movement on the member 20 to effect the reversal of the guides 10 and 11, as previously mentioned. The member 20 consists of a base bar 22 on which is mounted for vertical movement a lower guide rail 23 which is held in engagement with the lower portion of the trackway 19 by a yielding pressure created by the leaf spring 24, the intermediate portion of which, is secured at 25 to the bottom edge of the bar 22 and the ends of said spring engaging the lower edge of said guide rail so as to exert an upper pressure thereagainst. Intermediate the ends of the bar 22 the same is provided with an upstanding portion 26 having along its upper edge a flange 27 grooved at 28 to form a guide which is adapted to receive the upper edge of the trackway 19. To mount the guide rail 23 on the bar 22, the former has extending therefrom two headed pins 29 which extend through vertical slots 30 in the bar 22 so as to permit of vertical movement of said guide rail and consequent frictional engagement thereof with the bottom of the trackway under the influence of the spring 24.

The other member 21 of the carrier, which is movable longitudinally of the member 20, is in the form of a plate 31 supported upon the bar 22 by an enlargement 31a and held in position thereagainst by the heads of the pins 29, said plate having longitudinal slots 32 therein of greater width than the diameter of the pins 29 so as to allow for the vertical movement thereof when the guide rail 23 is forced downwardly against the tension of the spring 24 and upwardly into engagement with the trackway 19 under the influence of said spring. The length of said slots is equal to the extent of the longitudinal movement of the member 21 when it is adjusted back and forth on the member 20 and said pins act to engage the ends of said slots to limit said movements. At each end of the plate 31 the same is increased in thickness as indicated at 33 (Fig. 4) and this enlarged portion is provided with a vertically disposed flange 34 having in its lower edge a groove 35 adapted to receive the upper edge of the trackway 19. The upper ends of the flanges 34 at each extremity of the plate 31 extend above the upper edge of the portion 26 of the member 20 and constitute abutments which are adapted to be alternately engaged by the propelling mechanism, presently to be described, which acts to move the member 21 that includes the plate 31 longitudinally and relative to the member 20, and then move the two members of the carrier in unison over the needles of the machine.

As best shown in Figure 6, the angular support 36 for the yarn guide 11 has its upper end secured at 37 to the inner surface of the bar 22, and the lower end of said support has the upper end of the spring arm 17 attached thereto. An angular support 38 for the guide 10 has its upper portion 39 recessed in the rear of the plate 31 of the movable member of the carrier and is attached to said plate by a screw 40 that extends through a vertically disposed slot 41 formed in said portion 39 whereby a vertical adjustment of the supporting member, and consequently of the guide 10, relative to the needles of the machine 70 and to the guide 11, may be secured. The upper extremity of the support 38 is provided with eyelets 42 and medially of said support other eyelets 43 are provided through which the yarns 13 and 14 are extended, the yarn 13 continuing 75

from an eyelet 43 through a guide slot 44 formed in an enlargement 45 at the lower extremity of the support 38, while the yarn 14 extends diagonally downward from the other eyelet 43 directly to the guide 11.

The propelling mechanism for the yarn carrier 12 may be of a conventional type such as used on link and link knitting machines, as disclosed, for instance, in our co-pending application, Serial Number 143,964, filed May 21, 1937. Briefly this mechanism is mounted upon the reciprocating carriage of the machine and includes a beam 46 upon which is mounted the propelling mechanism, generally indicated by the numeral 15 47. This includes the usual plurality of headed propelling pins 48 only one of which need be employed in a plating operation since only one yarn carrier is used in the embodiment of the invention being described. In the usual manner, said pin is vertically adjustable so that it can be lowered into an operative position relative to the yarn carrier, as indicated in Figures 1 and 6, and when thus positioned the lower end of the pin is located in the space between the 20 abutments 34 at opposite ends of the movable member 21 of the carrier so as to alternately engage said abutments as the main carriage of the machine is reciprocating. Assuming, as shown in Figure 1, that the yarn carrier has 25 reached the end of its movement in the right hand direction and the main carriage of the machine is about to start its return movement. As this occurs, the pin 48 of the propelling mechanism first moves to the other end of the space 30 between the abutments 34. The left hand abutment 34 is then engaged by said pin and continued movement of the latter in the left hand direction acts to move the member 21 of the carrier in a left hand direction, as shown in Figure 35 2, until the right hand end of the portion 26 of the member 20 is contacted by the right hand abutment 34. During this movement the member 20 remains stationary due to the pressure of the spring 24 against the rail 23 and the consequent frictional engagement of the trackway 19 40 created thereby, but as soon as the limit of the left hand movement of the member 21 is reached, the continuing movement of the propelling pin 48 to the left then moves the two members 20 and 21 in unison across the machine. When the member 21 is shifted, as just described, from the 45 position of Figure 1 to that of Figure 2, the guide 10 carried by the movable member is shifted therewith so that it will be adjusted to the position of Figure 2 and thus reversed relative to the guide 11 so that the latter will follow the guide 10 during the movement of the carrier in the left hand direction, just as it did in the previous movement in the right hand direction.

50 In the form of device shown in Figures 7 and 8, instead of employing a single carrier for both guides 10 and 11, there is provided a separate carrier for each guide mounted on a separate trackway 19 of the machine. Thus the guide 10 has its support 38 secured to and vertically adjustable on a carrier 49, while the support 36 of the guide 11 is likewise secured to a carrier 50. The carrier 49 is provided with spaced abutments 51, similar to the abutments 34, and the carrier 50 is likewise provided with abutments 52. In order that the relative movement between the two carriers 49, 50 may be effected so as to accomplish the reversal of the relative positions of the guides 10, 11 such as previously described, 55 the distance between the abutments 51 on the

carrier 49 is less than that between the abutments 52 on the carrier 50. With this arrangement, when the propelling pins 48, one of which is used for each of the carriers in the present embodiment, are moved to the left, as shown in Figure 8, the pin 48 associated with the carrier 49 engages the left hand abutment 51 of the latter before the propelling pin associated with the carrier 50 engages its left hand abutment 52 and consequently, when the left hand abutment 51 of the carrier 49 is contacted by the pin 48, said carrier will be moved to the left and relative to the carrier 50 to shift the guide 10 from the position of Figure 8 to a point on the opposite side of the guide 11. When this movement has been completed the left hand abutments 51 and 52 of the two carriers are transversely aligned and from this point the two associated propelling pins will move the two carriers in unison across the machine.

What is claimed is:

1. In a knitting machine, a yarn carrier comprising two members one of which is supported for longitudinal movements on the other, said members having cooperating means to mount said carrier for reciprocating movements on a trackway, a guide carried by each of said members for feeding separate yarns to the needles of the machine, and means to move the first named member along the other member to alter the positions of said guides relative to each other when the direction of movement of said carrier is changed.

2. In a knitting machine, a yarn carrier comprising two members one of which is supported for longitudinal movements on the other, said members having cooperating means to mount said carrier for reciprocating movements on a trackway, said means including a rail on one of said members, means to maintain a yielding pressure on said rail against said trackway, a guide carried by each of said members for feeding separate yarns to the needles of the machine and arranged thereon so that one guide will follow the other during the reciprocating movements of said carrier, and means effective when the direction of movement of said carrier is changed to move one of said members longitudinally of the other member so that the first named guide will again follow said other guide.

3. In a knitting machine, a yarn carrier comprising two members one of which is supported for longitudinal movements on the other, said members having cooperating means to mount said carrier for reciprocating movements on a trackway, a guide carried by each of said members for feeding separate yarns to the needles of the machine, means to mount one of said guides for vertical adjustments on its member, and means operable, when the direction of movement of said carrier is changed, to move the first named member along the other member so as to alter the positions of said guides relative to each other.

4. In a knitting machine, a yarn carrier comprising two members one of which is supported for relative longitudinal movements on the other, a rail on one of said members for mounting the carrier for reciprocating movements on a trackway, means maintaining a yielding pressure on said rail against said trackway, a guide on each member, flexible mountings for said guides extending from said members and permitting the guides to swing laterally relative to the direction of movement of the carrier, said mountings supporting one of said guides in leading relation to

the other, and means to move the first named member longitudinally of the other upon a reversal of the movement of said carrier.

5. In a knitting machine, a yarn carrier comprising two members one of which is slideable on the other and provided with abutments, and the latter member having means to limit said sliding movement, means movable between said abut-

ments and engageable therewith to initially slide the first named member relative to the other member and thereafter propel said carrier as a unit in either one of two directions, and yarn guides carried by said members.
